United States Patent Office.

SAMUEL KELLETT, OF SAN FRANCISCO, CALIFORNIA.

Design No. 2,554, dated January 15, 1867.

DESIGN FOR A MOULDING.

The Schedule referred to in these Letters Patent and making part of the same.

TO ALL WHOM IT MAY CONCERN:

Be it known that I, SAMUEL KELLETT, of the city and county of San Francisco, State of California, have originated and designed a new pattern for "Mouldings" for cornices to buildings, of which the following is a full, clear, and exact description, reference being had to the accompanying "photograph," making a part of this specification.

My design consists of a moulding to be planted in the cove of cornices, for the decoration of buildings, and is composed of plaster of Paris, so-called, prepared in the usual way.

The foundation of my design is scroll-work, of the pattern shown. I place in the curves along this scroll the following collections of figures, viz, A, B, C, D, alternately, as shown in the print.

Figure A is composed of a black radish, an almond, a nutmeg melon, a pear and leaves, and a bunch of grapes.

Figure B, a pear, apple, lemon, a plum, a nut, and a bunch of grapes.

Figures C and D consist of a bunch containing three daisies and their leaves.

I prefer to cast the figures in gelatine moulds, as a higher relief is imparted to my design by this manner of casting.

Having thus described my invention, what I claim, and desire to secure by Letters Patent, is—

The design for mouldings for buildings, as shown and described.

In witness whereof I have hereunto set my hand and seal this 25th day of September, 1866.

SAM'L. KELLETT. [L. S.]
